UNITED STATES PATENT OFFICE.

FREDERICK W. BLACKHALL, OF FORT ERIE, ONTARIO, CANADA, ASSIGNOR OF ONE-HALF TO
GEORGE B. HINKLEY, OF BUFFALO, NEW YORK.

PRINTER'S QUOIN.

No. 877,039.

Specification of Letters Patent.

Patented Jan. 21, 1908.

Application filed April 3, 1907, Serial No. 366,228.

To all whom it may concern:

Be it known that I, FREDERICK W. BLACKHALL, a subject of the King of England, residing at Fort Erie, in the Province of Ontario and Dominion of Canada, have invented a new and useful Improvement in Printers' Quoins, of which the following is a specification.

This invention relates to the class of 10 printers' quoins comprising a pair of wedge-shaped sections having opposing gear racks adapted to receive the pinion of the customary key by which they are tightened and loosened, and more particularly to quoins of 15 this kind having automatic catches for preventing slipping or loosening of the wedges on each other by the jarring of the printing press.

The object of my invention is to provide 20 the quoin-sections with a simple and effective automatic lock of this character which does not materially increase the cost of the quoin.

In the accompanying drawings: Figure 1 25 is a side elevation of the quoin. Fig. 2 is a central longitudinal section thereof. Fig. 3 is a face view of one of its sections. Fig. 4 is a perspective view of one of the sections.

Similar letters of reference indicate corresponding parts throughout the several views.

A, A indicate the two wedge-shaped sections of the quoin each preferably provided on its face with the customary longitudinal central rib b which has an inclined face and 35 slides in a groove or recess c in the face of the inwardly-projecting lug C forming the large end of the section. On opposite sides of their central ribs b, the sections are provided with the usual gear racks d which are de- 40 pressed below the faces of the ribs and adapted to be engaged by the gear pinion D of the customary operating key.

Secured to the back of each section is a 45 flat spring E extending lengthwise thereof and having its free end portion bent inwardly and arranged adjacent to and substantially parallel with the large end of the section, to form a spring-tooth or catch e. This catch is adapted to interlock with one of a series 50 of teeth b¹ formed in the face of the rib of the other section, as shown in Fig. 2, to prevent slipping of the sections on each other and unlocking of the same under the jarring or vibration of the printing press.

As shown in Figs. 2 and 3, the body of each

spring E is countersunk in a longitudinal groove g formed in the back of the section while its tooth e is countersunk in a transverse groove or recess g¹ arranged in the large end of the section and forming a continuation of the groove g. The tooth e of each section projects normally beyond the toothed face of the rib of the same section, so as to interlock with the toothed rib of the opposing section when the two sections are placed face to face, as shown in Fig. 2. The rear ends of the springs E may be secured to the sections by rivets or other suitable means. In the preferred construction shown, the grooves g gradually increase in depth toward the large 60 ends of the sections and the springs follow the inclined bottoms of the grooves, which latter are deep enough to allow the springs to recede sufficiently to clear the toothed ribs in shifting the quoin-sections on each other. 65 The walls of the grooves g, g¹ hold the springs against lateral displacement and thus enable each spring to be fastened by a single rivet, as shown.

The teeth of the ribs b are preferably V- 70 shaped or inclined on both sides, as shown, so that the sections can be released or backed up by simply shifting them lengthwise on each other. While permitting of this action, these teeth and the spring-catches e hold the 75 sections with sufficient security to resist slipping and loosening of the same by the jarring of the printing press as above described.

The spring E and catch e of each quoin-section are formed of a single piece of spring-steel or other suitable material, producing a very simple construction which is not liable to get out of order and which adds but little to the cost of the quoin. Both parts of the 90 quoin including their locking catches are identical and they are therefore interchangeable like the corresponding sections of ordinary quoins of this class.

I claim as my invention:

1. A wedge-shaped quoin-section, provided on its face side with a toothed longitudinal rib, in its back with a longitudinal groove and in its large end with a groove forming a continuation of said longitudinal groove, and 100 a flat spring secured lengthwise in said longitudinal groove and having its free end portion bent inwardly and arranged in the end groove of the quoin section, said inwardly bent end extending beyond the face of said 105 110

toothed rib and forming a spring-tooth adapted to interlock with the corresponding rib of an opposing quoin-section, substantially as set forth.

5 2. A quoin comprising a pair of wedge-shaped sections, each provided on its face side with a longitudinal series of locking teeth, and a spring secured to the back of the section and having its free end bent inwardly
10 around the large end of the section, forming

a spring-tooth adapted to interlock with the teeth of the opposing section, substantially as set forth.

Witness my hand this 30th day of March, 1907.

FREDERICK W. BLACKHALL.
